UNITED STATES PATENT OFFICE.

HARRY B. HILLS, OF RIVERTON, NEW JERSEY, ASSIGNOR TO STEWARD DAVIT AND EQUIPMENT CORPORATION, OF NEW YORK, N. Y., A CORPORATION OF NEW YORK.

BOAT-LAUNCHING CARRIAGE.

1,311,446.

Specification of Letters Patent. Patented July 29, 1919.

Application filed November 22, 1918. Serial No. 263,671.

To all whom it may concern:

Be it known that I, HARRY B. HILLS, a citizen of the United States of America, residing in Riverton, in the county of Burlington, 5 ton, in the State of New Jersey, have invented certain new and useful Improvements in Boat-Launching Carriages, of which the following is a true and exact description, reference being had to the accompanying drawings, which form a part thereof.

My invention relates to life boats, and has for its object to provide a boat launching carriage adapted for temporary attachment 15 to one side of a life boat and so constructed as to facilitate the launching of the boat over a ship's side, and at the same time to protect the boat from injury by striking against the side of the ship.

20 The nature of my invention will be best understood as described in connection with the drawings in which it is illustrated and in which

Figure 1 is a side elevation of a life boat 25 equipped with my improved launching carriage.

Fig. 2 is an end view of the boat and carriage, with portions of the side of the boat broken away so as to show the mode 30 of attachment of the carriage to the boat.

Fig. 3 is a longitudinal section through the carriage on the line 3—3 of Fig. 1, and

Fig. 4 is a fragmentary view similar to Fig. 3, showing a modification of the means 35 for connecting the wheels of the carriage to the buffer bar.

A is the boat, A'A', Fig. 2, the gunwales of the boat, BB indicate suspension cables by which the boat can be connected to the 40 davits, not shown.

C is a buffer bar shaped to extend over and fit against a considerable portion of the side of the boat, its inner face C³ being conformed approximately to such curvature as 45 the boat may have. As shown, the buffer bar is formed with slots C'C', extending in from its face; the bottom of the slot in Fig. 3 being shown as having a cam like curve for a purpose which will be explained. DD, 50 Fig. 3, are spring bars located in the slots C', and having their inner ends firmly secured to the buffer bar as by bolts indicated at EE. On the outer ends of these spring bars are secured wheels FF, which normally 55 project beyond the face of the buffer bar C,

as indicated in Fig. 2, but which, in case of the boat swinging against the side of the ship with a considerable force will be pressed back until they are flush with the outer surface of the buffer bar C, the springs DD 60 yielding and the cam surfaces C²C² of the slots C'C' affording a progressive support to the spring bars D as they are bent inward, so that they will act with constantly increasing force.

65 In the modification illustrated in Fig. 4 the bar DD is not a spring bar, but is pivotally attached at G' to a plate G held in place on the buffer bar by a bolt E, and having its outer end spring supported as by 70 a coiled spring H. In other respects the construction is similar to that of Fig. 3 except that the bottom of the slot need not have the curved cam shape illustrated in Fig. 3.

II are brackets secured to the buffer bar 75 C and supporting hooks indicated at I', which hook over the gunwales of the boat as shown in Fig. 2. As shown, the brackets I are formed with an inclined under surface I³, which materially facilitates the launching of the boat as it is swung over the edge of the ship when the ship is so heeled over that the boat does not swing clear. I² indicates a projecting end of the bracket I; to each of these ends is attached a cable J which 80 is passed under the bottom of the boat and which has its free end J' attached in any convenient way to the opposite edge of the boat from that to which the launching carriage is attached. As shown, the cables J 85 are attached with cleats indicated at A². K, Fig. 2, indicates the side of a ship with the launching carriage resting against it.

90 It is, of course, apparent that in the launching of the life boat, equipped with my improved launching carriage, over the side of the ship, any tendency of the boat to swing inward against the side of the ship will result in the wheels F of the carriage coming in contact with the ship's side, 100 as shown in Fig. 2. This will prevent injurious scraping of the side of the boat against the side of the ship and facilitate the downward movement of the boat. In case the boat swings violently against the 105 ship's side, the wheels F being spring supported, will be pushed toward the side of the boat until they are flush with the buffer bar C, which bar will take up whatever force of the blow is left after the compression of 110

the springs and transmit it to a very considerable portion of the side of the boat, which is thus protected against what would be apt to be destructive blows if no buffer bar were supplied.

When the boat is in the water the carriage can readily be removed from it, and can be released, or may usefully be retained to serve as a sea anchor.

10 It will, of course, be obvious that my invention is capable of considerable modification without departure from its spirit and that the special form I have illustrated as shown is what I believe to be its best practical embodiment for use.

Having now described my invention, what I claim as new and desire to secure by Letters Patent, is:

20 1. A boat launching carriage consisting of a continuous longitudinally extending buffer bar formed to fit against and over a considerable length of the side of the boat, in combination with wheels secured to the ends of the buffer bar and extending beyond its outer surface, and means for detachably securing the buffer bar to the side of the boat.

25 2. A boat launching carriage consisting of a buffer bar formed to fit along and over

a considerable length of the side of the boat, 30 in combination with wheels spring supported at the ends of the buffer bar and normally projecting beyond the face of the bar, and means for detachably securing the buffer bar to the side of the boat.

35

3. A boat launching carriage consisting of a buffer bar formed to fit along and over a considerable length of the side of the boat, in combination with wheels secured to the ends of the buffer bar, hook brackets 40 secured to the buffer bar and adapted to hook over the edge of the boat and cables attached to the bar and adapted to pass under the boat to be secured at its opposite edge.

45

4. A boat launching carriage consisting of a buffer bar formed to fit along and over a considerable length of the side of the boat, in combination with wheels secured to the ends of the buffer bar, hook brackets 50 secured to the buffer bar and adapted to hook over, said brackets being formed with inclined sides extending from the buffer bar toward the bottom of the boat, and cables attached to the lower ends of the brackets 55 and adapted to pass under the boat and to be attached to its opposite edge.

HARRY B. HILLS.
